UNITED STATES PATENT OFFICE

116,112

DESIGN FOR A RAIL CAR TRUCK

Robert J. Burrows and Alfred O. Williams, Battle Creek, Mich., assignors to Clark Equipment Company, Buchanan, Mich., a corporation of Michigan

Application January 24, 1938, Serial No. 74,505

Term of patent 14 years

To all whom it may concern:

Be it known that we, Robert J. Burrows and Alfred O. Williams, citizens of the United States, residing at Battle Creek, in the county of Calhoun and State of Michigan, have invented a certain new, original, and ornamental Design for a Rail Car Truck, of which the following is a specification, reference being had to the accompanying drawing, forming a part thereof.

In the drawing:

Figure 1 is a side elevational view of a truck showing our new design, with the left hand side

of the figure having the wheel removed and a section taken through the axle on line 1—1 of Fig. 3.

Figure 2 is an end view of the truck shown in Figure 1; and

Figure 3 is a top plan view of the truck showing the new design.

We claim:

The ornamental design for a rail car truck, as shown.

ROBERT J. BURROWS.
ALFRED O. WILLIAMS.
